UNITED STATES PATENT OFFICE.

WARNER R. BUXTON, OF LONGMEADOW, MASSACHUSETTS.

KEY CASE.

Application filed January 14, 1925. Serial No. 2,333.

This invention lies in the key case art and relates primarily to improvements in the support, through the intermediary of which the key holders are pivotally connected to the folder of the key case.

The invention marks a distinct and most important step in the development of the key case art in that it is directed to the improvement of the key holder support. These supports, as found in the trade in practical and commercial types, have changed very little from the early forms in which they were originally developed, notwithstanding that wide and rapid developments have been made in the key case art along other lines. The early form of support, shown in my prior U. S. Letters Patent No. 1,261,692, dated April 2, 1918, included two struck up ears to which the ends of a pivot rod were fastened. This type of support was soon displaced by that shown in my U. S. Letters Patent No. 1,423,909, in which the upper edge of the support was rolled over to encompass the pivot rod and was transversely slotted to receive the key holders. On the development of the so called swivel key case, exemplified by U. S. Letters Patent No. 1,404,736, granted January 31, 1922, on an invention of Frank G. Bowen, substantially the same type of support was used to afford sockets to receive the ball heads of the key holders. The commercial swivel key case includes a support very much like that of the Bowen patent but having a rolled over portion of much smaller diameter in which the ball heads of hooks, made as disclosed in my prior U. S. Letters Patent No. 1,439,863, granted December 26, 1922, are received. The present invention solves the problem of providing a better support than any heretofore used, from both the manufacturer's and user's point of view, and with it a better key case, in appearance, usefulness, strength and useful life.

The key holder support of this invention constitutes a wide departure from present and former standards and is essentially characterized in that it is constructed in separate parts, between which the key holders are held in a manner to permit their usual movements, and in that these parts are held together by their interengagement without the aid of other fastening means, whereby the parts and the key holders may be interengaged and disengaged with convenience, as desired.

To the manufacturer, the key holder support of this invention offers better manufacturing conditions. It can be made with improved accuracy by simple manufacturing methods adapted to result in uniformity of product under the conditions of quantity production manufacture. It can be made smaller in size, of thinner metal and at the same time be stronger and far more attractive in appearance than prior art supports. Its parts can be separately and completely formed prior to placing the hooks or key holders therein and the assembly of the parts and of the hooks can be accomplished rapidly by unskilled labor without the aid of tools. From both the points of view of manufacturer and user, a key case, having the key holder support of this invention, is a better article,—stronger, neater, more attractive in appearance, and calculated to give greater and extended service over the types heretofore prevalent. To the user, the invention also provides means whereby he is enabled to readily and conveniently remove and replace the key holders at his will and pleasure, and yet ordinarily have them securely retained and connected to the case for operation in the normal manner.

There are many details contributing to the accomplishment of the broad objects above set forth, and these will appear from the following description taken with the illustrative embodiment of the invention in the accompanying drawings, in which:

Figs. 1 and 2 are enlarged perspective views of the back and front pieces of the support;

Fig. 3 is an enlarged front elevational view, showing such pieces interengaged and the key holders assembled therein;

Fig. 4 is an enlarged cross sectional view taken on the line 4—4 of Fig. 3;

Fig. 5 is an enlarged plan view of the front piece of the support;

Fig. 6 is a small scale view of an open key case including the support of this invention;

Figs. 7, 8 and 8^a are enlarged front elevational, cross sectional and plan views showing a modification in the support;

Fig. 9 is a still further enlarged cross sec-

tional view taken on the line 9—9 of Fig. 7;

Fig. 10 is an enlarged rear elevational view of the front piece taken prior to its assembly with the back piece;

5 Fig. 11 is a sectional plan view showing the manner of releasably holding the parts of the support together;

Fig. 12 is a small scale elevational view of a key case embodying the support shown in 10 Fig. 7; and

Fig. 13 is an enlarged and fragmentary cross sectional view taken on the line 13—13 of Fig. 12.

Referring to these drawings;—the key 15 holder support, in its simplest form, is shown in Figs. 1 to 6 inclusive. It consists of two parts,—a back piece 15 shown in Fig. 1, and a front piece 16 shown in Fig. 2, which parts are constructed so as to be conveniently interengaged and frictionally held together by 20 their interengagement in the normal assembled relation shown in Figs. 3 and 4. As shown, opposite edges of the back piece have been rolled over to form flanges 17, the inner 25 faces of which are spaced from the body of the back piece to form a slideway 18. The back piece is also provided with suitable means, such as the holes 19, whereby it may be attached, as by the usual rivets 20 to the 30 central portion of the folder of the key case A near the upper edge thereof. The front piece 16, as shown, is stamped out to form flanges 21 to fit in the slideway 18 and a forwardly bulged portion 22, of approximately 35 semi-circular cross sectional shape, forming a recess 23 which is open at the back but adapted to be closed by the back piece 15 when interengaged with the latter.

The key holders, such as the snap-hooks *h*, 40 are adapted to be retained between the interengaged but conveniently separable parts 15 and 16 in a manner to permit them to swing into and out of the key case and desirably, although not necessarily, in a manner to permit 45 them to swivel, as well. Since the swivel feature is generally desired, I have chosen to illustrate a support adapted for this purpose, as being the best and most useful form of the invention but recognizing that the invention is not confined to this feature. For 50 the swivel feature, the recess 23 constitutes a socket to receive the ball heads *i* of the key holders (see Fig. 4) in a manner to permit the holders to swing and swivel in the usual 55 way. The forwardly bulged portion 22 is provided with a series of longitudinally spaced and transversely disposed slots 24 in which the necked down portions *j*, of less width than the diameter of the ball heads *i* 60 and of the key holders, are received and by which slots the key holders are guided in their swinging movement.

Suitable provision is made to enable the necked down portions *j* of the key holders *h* 65 to pass into the slots 24 and, as one example,

the slots may be made, as shown, to extend to one edge of the front piece 16, preferably the upper edge. The key holder *h* may be rapidly and conveniently assembled in the front piece 16 prior to its engagement with the back piece 15. The front piece is held so that the open ends of the slots 24 are uppermost and the hooks *h* are successively inserted in place. To do this, the hook is held upside down with its ball head *i* positioned adjacent the recess 23 in the rear of the front piece 16 and the hook is moved forwardly to carry the necked down portion *j* into the slot 24 and the ball head *i* into the recess 23, after which the hook is swung downwardly into its normal pendant position. After all the hooks have been thus assembled, the front piece 16 is slid endwise into the slideway 18 in the back piece 15 and the two parts of the support are then so interengaged that the recess 23 and slots 24 are effectively closed to prevent the escape of the key holders.

The two parts of the key holder support may be held against relative movement in any suitable manner. As a practical matter, they may be held sufficiently for some purposes by frictional engagement. One of the parts, such as the front piece, may be bowed slightly, as shown in Fig. 5, so that when it is slid into the back piece it is straightened out and placed under stress and, in tending to resume its original bowed form, presses against the back piece with a spring-like action and creates sufficient friction between the parts to avoid unintentional relative movement therebetween.

Aside from the manufacturing advantage in conveniently assembling the key holders in their support, there is the important advantage of being able to remove a key holder from the support with equal convenience. The operation of removing a broken key holder and replacing it with a new one can be quickly and easily accomplished by anyone without the aid of any special tool. Also, the user of the key case can change the keyholders at his own will and pleasure. He need carry only such keys as he will need to use on a particular occasion since he may readily remove the key holders carrying the keys not then needed. The key holders may be removed from the support with much greater facility than the keys can be removed from the key holders because it is simply necessary to slide the front piece 16 out of the back piece 15 far enough to expose the slot 24 which contains the desired key holder. One is enabled to get along with a small key case by supplementing it with a number of extra key holders for the keys which are infrequently used and substituting the extra key holders for other key holders in the case whenever required.

While the keys may be removed and re-

placed with the structure above described, a relatively large degree of shifting movement of the two parts of the key holder support is required to reach certain of the 5 key holders and moreover all of the key holders are not simultaneously accessible for removal. To overcome these difficulties and provide a more convenient arrangement for the use who frequently wishes to change 10 around his keys, I provide the structure shown in Figs. 7 to 13 inclusive. This structure involves the essentials of that heretofore described, including the slidably interengaged front and back pieces 25 and 26 15 with a forwardly bulged and transversely slotted portion 27 in the front piece to provide for the reception of the key holders *h* in the general manner above described. In this case, however, the interengaged upper 20 flanges 28 and 29 of the front and back pieces 25 and 26 are disposed at an acute angle to the body of the back piece (see Fig. 9) and are somewhat wider than in the form above described. Also the transverse slots 25 do not extend to the upper edge of the front piece, but terminate adjacent thereto with enlargements 30 which are large enough to permit the heads *i* of the key holders to be passed therethrough. The upper flange 29 30 of the back piece is made to overlie these enlargements 30 when the assembled parts of the key holder occupy their normal relative positions shown in Fig. 7. This upper flange 29, however, is so constructed, as 35 for example by scalloping its lower edge, as shown at 31 that, on a relatively small shifting of the front and back pieces all of the enlargements 30 will be simultaneously exposed. Any or all of the key holders may 40 then be removed by swinging such key holder *h* upwardly until its head *i* comes under and can be pulled through the uncovered enlargement 30. As shown, the enlargements 30 may be uncovered by sliding 45 the front piece 26 to the right (as viewed in Fig. 7) a distance of not over half the center to center distance between successive key holders *h* or in other words, a less distance than the minimum distance required 50 with the first described form of the invention.

As with the first form of key holder support, the two parts may be held against unintentional displacement by any suitable means, such as those above described. Or the spring action of one part upon the other may be effected by a separate spring for the purpose. Thus, I have shown a flat spring 33 having at each end a pair of oppositely extending projections 34. (Fig. 10) designed to closely fit into corresponding recesses formed in the upper and lower flanges 28 of the front piece 26. This spring 33, which is disposed at the rear of the front piece 26 and partially closes the normal opening 35

in the rear end thereof, is made slightly longer than the distance between the pairs of recesses in which the projections 34 are to be received with the result that when the projections are engaged in these recesses, 70 the spring 33 is bowed rearwardly so as to press against the back piece 25 and create the desired friction between the parts.

It is desirable to limit the relative movement between the front and back pieces to 75 that necessary for the exposure of the enlargements 30 in slots 36. This enables the user to bring the two parts into the proper relative positions for the removal of the key holders without requiring any particular care or attention on his part. That is, he simply pushes the front piece 26 to the right (Fig. 7) as far as it will easily go and the enlargements 30 will be found to be completely uncovered and subsequently pushes 80 the front piece back until it reaches its normal limit and the enlargements will be found to be properly covered. As an illustrative example of one suitable way of accomplishing this function of conveniently 85 limiting the movement of the front and back pieces of the support, I provide at or near the central portion of spring 33 a slight projection 37, which is directed into a recess 38 (Fig. 11) in the body portion of the back piece 25. The length of this recess is such as to permit the projection to slide therein over the necessary distance as above defined. At each end of recess 38 is a depression 39 into which the projection 37 enters to releaseably hold the front piece 26 in either of the two positions into which it may be normally moved. The spring bears on the back piece at all times and frictionally holds 90 the two parts of the key holder against unintentional relative movement. At the same time the parts may be shifted readily enough, when desired, over the limited range necessary to uncover or cover the enlargements. However, additional resistance is exerted by 95 the spring 33 should further shifting of the parts beyond the normal limited range be attempted. The projection 37 rides out of recess 38 and is forced backwardly, placing the spring 33 under greater stress and thereby resisting separation of the parts. The increased frictional resistance does not prevent 100 complete separation of the parts, should this for any reason be necessary, but it does deter the user from accidentally separating the parts and saves him the annoyance of getting the parts properly reassembled.

The spring 33, as just described, may 105 obviously be equally well used with the first described form of the invention, if desired. The spring is useful, aside from its primary function, to retain the heads *i* of the key holders *h* in place prior to the interengagement of the front and back pieces. It keeps 110 the heads within their proper limits and 115

prevents a head *i* from protruding from its recess 35 and catching on the back piece 25 during assembly. It also guards against the possibility of a head *i* on a key holder moving rearwardly in normal operation and entering and becoming lodged in one of the hollow rivets 40 by which the back piece 25 is secured to the key case.

It is desirable to avoid sharp edges and corners at the ends of the key holder support since they tend to wear the leather flaps of the folder of the key case which flaps are repeatedly drawn over such ends. For this reason I prefer to bend down the ends of the outwardly bulged portion of the front piece so that generously rounded and approximately hemi-spherical end closures 41 are formed. The ends of the front piece 26, and the ends of the slideway in 20 the back piece 25, should be chamfered, or rounded off, to facilitate the interengagement of these parts.

It should be noted that each part of the support includes angularly bent portions 25 which greatly increase the stiffness of the parts and the resistance against bending, just as an angle iron is stiffer than a flat bar of equal thickness. As a consequence, the parts may be made of considerably thinner metal than has formerly been used. This advantage is increased by the use of two parts which may each be made quite thin and yet, when combined, present all the rigidity and stiffness desired. The 35 front piece, notwithstanding its weakening by reason of the transverse slots is, nevertheless, sufficiently stiff due to the angle iron section at the lower part thereof which includes the solid lower flange and the adjoining right angularly turned part of the forwardly bulged portion. Increased stiffness of the front piece is afforded by the second form of the invention wherein the slots do not extend entirely through the 40 upper flange. It should be noted that the resistance to bending is very important for if the support is bent rearwardly into bowed form to a sufficient degree, the key holder slots will spread and allow the heads of the 45 key holders to pass therethrough.

From a manufacturing view point, each of the metal parts of the key case can be separately and completely formed and the parts later assembled without the use of 55 tools. Generally, either the key holder support or the key holders themselves, usually the former, have been only partially formed, leaving a bending operation to be performed after the assembly of the key holders in 60 their support. For example, the rolled over upper edge of the usual type of key holder support is not closed down until the heads of the key holders have all been inserted therein. A rather difficult operation is necessary to close down the roll of the usual 65

key holder support to encompass the heads of the key holders. Moreover, this rolling over operation leaves marks on the metal which are difficult to eradicate and mar the appearance of the case, especially the more 70 expensive cases having expensively plated metal parts. The parts of the present support may be formed by simpler manufacturing methods and the roll, or bulged portion, in the front piece may be stamped out with 75 precision producing a far more accurately formed, better working and smoother article than can be accomplished with the prior practice, which involved bending or rolling over the edge of the support as the parts 80 were assembled.

Aside from the advantages in the manufacture of the metal parts, the manufacturer secures decided advantages in the assembling 85 of the parts, which may not only be effected with convenience and dispatch in the simple manner already described, but can be effected by unskilled labor and without the use of tools or machinery. The rigid inspection, necessary heretofore where the 90 socket portion of the support was formed by bending methods which were difficult to perform with uniform accuracy even by skilled operatives, is avoided because the socket portion can be die stamped with accuracy and 95 precision and a uniform product results with simpler manufacturing methods capable of being much more speedily performed.

Aside from the improvement in the support itself, a better key case results from 100 the use of the support. The appearance of the case, a most important item to the trade, is materially improved by the reduction of the area of the key holder support. The flat plate depending from the socket portion of 105 former types of supports is entirely avoided and the unsightly rivets, formerly passing through such plate, are concealed behind the front piece. The plate, referred to, was so located as to be engaged and scratched by 110 the ends of the keyholder adjacent the entrance to the key retaining loop and the elimination of the plate overcomes this trouble, which was especially objectionable in high priced, expensively plated models 115 and resulted in an early marring of an attractive finish. The location of the rivets is important for other reasons than their concealment. They are applied to the support as closely as possible to the point at 120 which the load from the key holders and the keys is applied. The cantilever effect, due to the weight of the keys acting on the support at a considerable distance above the rivets, as with former methods, is avoided 125 and with it the tendency of the upper part of the support to pull away from the leather folder and render the case unsightly in appearance.

Entire concealment of the rivets may be 130

effected by applying the support to a flap such as 45 (Figs. 12 and 13) which is stitched to the key case folder A,—the outer ends of the rivets 40 being concealed between the flap and folder. Often such flaps are stitched to the key case only along their upper ends so that the flap can be swung upwardly to gain access to a pocket on the rear face of the flap. A key case of this type is shown in my prior U. S. Letters Patent No. 1,443,987, granted January 30, 1923. The flap usually bends along the lower edge of the key holder support and the support of this invention, by reason of its exceedingly small width, is especially useful with this type of case in that it affords increased freedom of access to the pocket by enabling the flap to bend along a line higher up on the case than was formerly possible.

The user of a key case, embodying the support of this invention has a better article, stronger, more attractive in appearance and better calculated to retain its initial attractive appearance, an important consideration when one buys an expensive, nicely-plated model. The purchaser of an expensive model does not have to throw the case away if by chance a key holder should become broken. A new key holder can be obtained and easily and quickly substituted. Not only this, but he is enabled to shift, rearrange and exchange key holders in the case according to his individual whims or desires. It enables one to conveniently lay aside the key holders, which carry keys not often used, placing them in the key case only when they are likely to be needed. One can thereby avoid carrying a heavy and bulky case, such as might be necessary for all one's keys, by using extra key holders in conjunction with a smaller case and loading the case up with the desired key holders at the start of the day.

The invention therefore marks a wide departure from present and former standards and provides a greatly improved key holder support which offers important advantages both to the manufacturer and user and which contributes to the production of a materially improved key case.

The invention has been disclosed herein for illustrative purposes but the scope of the invention is defined by the appended claims rather than by the foregoing description.

What I claim is:

1. A key case comprising a flexible sheet of protecting material foldable on itself to cover keys and a stiff key supporting device, said device including a relatively narrow back support fastened adjacent an edge of said sheet, a front support of substantially the same area as the back support and superimposed thereon, key holders removably mounted in the front support for independent pivotal movement, means on the

back support to prevent the removal of said key holders, said front support having a movable mounting on the back support whereby the user may move the front support out of the range of said means to release the key holders for removal from the case as desired. 70

2. A key supporting device for a key case comprising a back support, a front support, key holders removably mounted in the front support for independent pivotal movement, means on the back support to prevent the removal of the key holders, said front support having a movable mounting on the back support for the user to place the parts within 75 and outside of the range of said means whereby the key holders may be held in position or removed from the front support as desired. 80

3. A key supporting device for a key case comprising a back support, a front support movably mounted on the back support and having a plurality of spaced slots, key holders mounted in said slots and removable at one end thereof, means on the back support 85 to prevent the removal of the key holders at such end, said front support being movable to place the ends of its slots within the range and outside the range of said means whereby the user may remove the key holders when 90 desired. 95

4. A device for supporting keys in a key case comprising two supports mounted together for relative sliding movements, key holders removably mounted in one support 100 for independent movement, means on the other support to prevent the removal of the key holders when the supports are in one relative position and to permit such removal when they are in another relative position 105 and means tending to resist the movements of such supports from one relative position to the other.

5. A device for supporting keys in a key case comprising two supports mounted together for relative sliding movements, independent key holders removably mounted in spaced relation in one of said supports, spaced means on the other support corresponding to said spaced key holders to prevent the removal of the key holders when the supports are in that relative position for said means to register with the key holders and to permit such removal when the supports are moved to that relative position 110 where said spaced means and key holders are staggered, all constructed and arranged for the device to normally retain the key holders on the device, but to permit the user to remove and replace them when desired. 115

6. A device for supporting keys in a key case comprising, a series of key holders having heads by means of which they are pivotally supported, and supporting means therefor comprising two slidably connected 120 125 130

parts between which said heads are encompassed.

7. The combination in a key case of a support for the key holders thereof, comprising, 5 a back part, means for fastening the same to the case, and a front part for pivotally supporting the key holders, said front part being interengaged with the back part and serving to conceal said fastening means.

10. 8. A key holder support, comprising, interengaged and relatively shiftable parts by 15 which the key holders are supported for swinging movement, one of said parts having openings through which the key holders may be removed, the other part when in one 20 position serving to cover said openings and when shifted to another position to uncover the same, and means resisting relative shifting of said parts and tending to hold the last named part in the first named position.

9. A key holder support comprising, interengaged and relatively shiftable parts by 25 which the key holders are supported for swinging movement, one of said parts having openings through which the keyholders may be removed, the other part when in one position serving to cover said openings but when shifted to another position serving to 30 uncover the same, and means for limiting

the relative shifting movement of said parts to the predetermined range necessary to allow the covering and uncovering of said openings.

10. A key holder support, comprising, interengaged and relatively shiftable parts by 30 which the key holders are supported for swinging movement, one of said parts having openings through which the key holders may be removed, the other part when in one 35 position serving to cover said openings but when shifted to another position serving to uncover the same, and means for resisting relative shifting of said parts constructed to exert increasing resistance when the parts 40 are shifted beyond the range necessary to cover and uncover said openings.

11. A key holder support comprising interengaged and relatively shiftable parts 45 from which the key holders are supported for swinging movement, and openings provided in one of said parts through which the key holders may be removed, the other part when in one position serving to cover said 50 openings but when shifted to another position serving to uncover the same.

In testimony whereof I have affixed my signature.

WARNER R. BUXTON.
